CLAIM

I claim the ornamental design for an under self merchandise support bracket, as shown and described.

DESCRIPTION

FIG. 1 is a perspective view of the under shelf merchandise support bracket according to the present design;

FIG. 2 a right side view of the present design;

FIG. 3 is a left side view of the present design;

FIG. 4 is a front view of the present design;

FIG. 5 is a rear view of the present design;

FIG. 6 is a top view of present design;

FIG. 7 is a bottom view of the present design; and,

FIG. 8 is an environmental view of the support bracket of the present design in use with a strip display and an associated horizontal shelf.

The broken line showing of hooks, a portion of a shelf and the label on the bracket is for illustrative purposes only and forms no part of the claimed design.
